UNITED STATES PATENT OFFICE.

ELIJAH B. BENHAM, OF HOLYOKE, MASSACHUSETTS.

PITMAN-AND-CRANK CONNECTION.

SPECIFICATION forming part of Letters Patent No. 380,850, dated April 10, 1888.

Application filed August 29, 1887. Serial No. 248,143. (No model.)

To all whom it may concern:

Be it known that I, ELIJAH B. BENHAM, a citizen of the United States, residing at Holyoke, in the county of Hampden and State of Massachusetts, have invented new and useful Improvements in Pitman-and-Crank Connections, of which the following is a specification.

This invention relates to pitman-and-crank connections for engines and other machines, the object being to provide an improved construction for the end of the pitman which engages with the crank-pin and means for securing it to the latter, said improvements being particularly adapted to multiple-cylinder engines; and the invention consists in the peculiar construction of the crank-pin ends of the pitmen, together with means for attaching them to said crank-pins, all as hereinafter fully described, and pointed out in the claims.

In the drawings forming part of this specification, Figure 1 is a front elevation of a multiple-cylinder engine having pitmen embodying my improvements, said figure illustrating the end of the crank-pin and the ends 25 of the pitmen surrounding the latter, with the crank-pin cup removed, and showing the side of one of the cylinders broken away. Fig. 2 is a perspective view of the crank and a portion of the driving-shaft of the engine, together 30 with the ends of two of the pitmen, showing the crank-pin cup and its securing-nut in section.

In the drawings, 2 indicates the cylinders of the engine radiating from a common center, and provided with suitable pistons, *b*, each of said pistons having attached thereto a pitman, *3*. The shaft 8 of the engine extends rearwardly from a central point between the inner ends of the cylinders 2, and has 35 thereon the crank *B*, of which 6 is the crank-pin having the reduced screw-threaded end 7. A steel sleeve, 5, is fitted onto said crank-pin, and is preferably hardened to provide a bearing for the ends of the pitmen of greater durability than iron or softer metal than steel, thereby reducing the friction between the crank-pin and the pitmen.

K, Fig. 1, indicates a part of the standard on which the engine is supported. Each of 50 said pitmen 3 is provided with an arm, 4, on its lower end, or that which is connected to the crank-pin, at right angles to the length of the pitman and extending toward the end of

said pin. Each of said pitman-arms has formed thereon a lateral offset, *a*, whereby the 55 end of the pitman is caused to have a broad base, which rests against the sleeve 5 on the crank-pin.

In Fig. 2, 8 indicates a portion of the driving-shaft of the engine, extending from the 60 rear side of the crank *B*, said shaft being indicated by dotted lines in Fig. 1.

The said arms 4 of the pitmen are locked together on the sleeve 5 of the crank-pin 6 by the cylindrical cup 9, which fits over said 65 arms, as shown in Fig. 2, and a nut, 10, screwed onto the said reduced end 7 of the crank-pin holds said cup onto the latter and over the arms of the pitmen in the position shown.

What I claim as my invention is—

1. The within described pitman-and-crank connection, consisting of the combination, with the pin of the crank, of the sleeve 5, inclosing said pin, a series of pitmen, each having 75 an arm extending at right angles thereto toward the end of the crank-pin and bearing on the sides of said sleeve, and a cylindrical cup, 9, secured against the end of the crank-pin and inclosing the arms of the pitmen, substantially as set forth.

2. The within-described pitman-and-crank connection, consisting of the combination, with the pin of the crank, of the sleeve 5, inclosing said pin, a series of pitmen, each having 85 an arm extending at right angles thereto toward the end of the crank-pin bearing on the sides of said sleeve, said arms having a lateral offset, *a*, on one side, and a cylindrical cup, 9, secured against the end of the crank-pin 90 and inclosing the arms of the pitmen, substantially as set forth.

3. The within-described pitman-and-crank connection, consisting of the combination, with the pin of the crank having the screw-threaded extension 7, of a sleeve covering said pin, a series of pitmen, each having an arm extending at right angles thereto toward the end of said pin and bearing on the sides of said sleeve, a cylindrical cup inclosing said pitman-arms 100 and crank-pin, and a nut screwing on said crank-pin extension, substantially as set forth.

ELIJAH B. BENHAM.
